UNITED STATES PATENT OFFICE.

WILLIAM W. DIXON, OF BOSTON, MASSACHUSETTS, ASSIGNOR TO REECE
BUTTON-HOLE MACHINE COMPANY, OF PORTLAND, MAINE.

BUTTONHOLE-STITCHING MACHINE.

SPECIFICATION forming part of Letters Patent No. 695,039, dated March 11, 1902.

Application filed May 2, 1898. Serial No. 679,412. (No model.)

To all whom it may concern:

Be it known that I, WILLIAM W. DIXON, of Boston, county of Suffolk, State of Massachusetts, have invented an Improvement in Buttonhole-Stitching Machines, of which the following description, in connection with the accompanying drawings, is a specification, like characters on the drawings representing like parts.

10 The invention herein to be described is intended as an improvement on the machine shown and described in United States Patent No. 498,216, dated May 23, 1893, my invention having been devised to improve the construction of that part of the stitch-forming mechanism located below the stitch-frame and designated in said patent as the "complemental stitch-forming mechanism," it coöperating with the eye-pointed needle carrying the up-20 per thread.

In the machine described in the patent referred to the looper and the needle or under-thread carrier derive their movements through a sliding cam-block grooved at its opposite 25 sides and having at one side a projecting cam, and in case either of said grooves becomes worn it is necessary to discard the cam-block and substitute another one for it. The cam-block is fitted to slide in a rotatable block 30 which has imparted to it at proper times a circular movement, as when the stitching is being made about the end of a buttonhole. The looper-carrier in said machine is made as a single one-piece lever bored to receive a stationary stud, which constitutes the fulcrum 35 for the lever, and said stud carried by the circularly-moving block is surrounded by a spring, said lever acted upon by the projecting cam of the sliding block being moved laterally on its said stud or fulcrum to insure 40 for the looper a movement such as required and fully described in said patent to enable it to travel in a curved path about the plane of movement of the under-thread carrier, said 45 looper at such time standing in and expanding the loop of needle-thread, so that it may be entered by the under-thread carrier as the latter rises through the buttonhole-slit. The under-thread carrier in said machine is shown 50 as a curved needle, having an eye to receive the under thread, and said thread-guide is

connected with a needle-carrier adapted to slide in an inclined raceway in said rotatable block, so that the thread-carrier in its movement travels in the arc of a circle which cuts a perpendicular plane in which reciprocates the eye-pointed needle. The needle-carrier derives its movement from a lever which is vibrated about an inclined stud, said lever having a roller or other stud, which enters a cam-groove cut in one side of said sliding block, the walls of said groove being warped or twisted to thereby enable the walls to contact as much as possible with said roller-stud throughout the operation of the cam thereon. 55 The parts so made when put into operation were found at times to be undesirable, for the reason that they were liable to break or wear unduly, and it was found impracticable to impart to the supplemental stitch-forming 60 means an excessively high speed, which it is desirable that a buttonhole-sewing machine shall have.

The improvements to be herein described were therefore devised especially to overcome 75 the objections found in the machine described, to simplify the operation of the parts, and also greatly increase the speed of the machine and its durability.

In the present invention the looper-carrier 80 has been divided into three separate detachable parts—viz., a main or body part pivoted on a stud extended from the rotatable block referred to, a swiveled part mounted on said body part and carrying the looper, and a cam 85 part having an irregular cam-groove, the cam part being fixed to the body part, as by a suitable screw. Novel means have been provided to turn the swiveled part upon the body part that the looper may have imparted to it 90 at the proper time a lateral movement with relation to the upper needle and the under-thread carrier in making the stitch provided for in said machine. To impart movement to the needle-carrier to which is attached the 95 under-thread carrier, a lever has been provided which may be vibrated in a plane parallel with the plane of inclination of the raceway and the path in which the needle-carrier moves. The lever for moving the needle-carrier is sustained by an eccentric mounted on an inclined pivot carried by the circularly- 100

moving block, and said lever is connected with the needle-carrier by means of a suitable link. The lever is shown as an arm having at one end a substantially right-angled projection made hollow and slotted from side to side, the hollow part of the arm receiving a slide, the arm and slide receiving a stud-screw connected with a rod or bar which is reciprocated vertically in the circularly-moving block, said rod or bar also carrying a stud which enters the slot in the cam part of the looper-carrier. By this rod or bar and the connections between it and the needle-carrier and the looper-carrier it is possible to actuate the under or curved needle and the looper at a high speed without the parts binding in any way due to the different lines or planes on which they are moved.

Figure 1 is a partial right-hand side elevation of a sewing-machine of the character referred to with my improvements added to enable the same to be understood. Fig. 1^a is a section in the line x , Fig. 1. Fig. 2 shows in elevation, but detached, the circularly-moving block containing the complemental stitch-forming mechanism referred to, said block being in position to show the looper-carrier and the needle-carrier to which is attached the under-thread carrier. Fig. 3 is a right-hand side elevation of the parts shown in Fig. 2. Fig. 4 is a left-hand side elevation of the parts shown in Fig. 2. Fig. 5 is a left-hand end view of the machine shown in Fig. 1, the clamp being shown in section, a portion of the cam-casing being also broken away to better expose the circularly-moving block mounted therein. Fig. 6 is a top or plan view of the parts shown in Fig. 2, said parts being, however, in the position shown in Fig. 5. Fig. 7 represents the several parts of the looper-carrier detached. Fig. 8 is a section in the line x' , Fig. 5, it showing the eccentric fulcrum supporting the lever employed to move the under-thread carrier. Fig. 9 is a section in the line x^2 , Fig. 5; Fig. 10, a section through the rod or bar 59; Fig. 11, a section taken through the screw e^{20} and the eccentric and parts surrounding it, and Fig. 12 is a section showing part of the circularly-moving block 48 and the rod or bar in it.

The clamp-frame a' , the casing a^4 , containing the needle-bar b' , it carrying an eye-pointed needle b'^x to manipulate the upper thread, said needle-bar and its casing being in practice mounted in a stitching-frame, (not shown,) the curb or cam casing a^4 , in practice secured to the movable stitching-frame, so as to travel with it under the clamp-frame, said casing having suitable adjustable headed bolts a^{44} , which bear against smooth ways a^{45} at the under side of the clamp-frame, the rod f^9 , deriving its motion from a cam in the stitch-frame, the cutter G^2 and its carrying-lever G , the under-thread carrier 51, the needle-carrier 50, to which it is attached, said carrier being fitted to slide in a groove or

raceway cut in a part 49, rising from and forming, preferably, a part of a block 48, having a circular upper end 48^x and adapted to have imparted to it at suitable times a circular movement, the gear 45, fast on a sleeve 48^{xx} of the said block 48, the tension device 80 for the under thread, the looper 63, and the throat-plate 52 are and may be all as shown and described in said Patent No. 498,216, and hence need not be herein further described.

The circular ring-like part a^{40} of the casing a^4 receives in it the circular upper end 48^x of the block 48, and said ring has depending from it a loop-like frame a^{41} , having made through it at its lower end a hole of suitable size to receive loosely the hollow hub 45^x of the gear 45, said gear being applied to the sleeve 48^{xx} of the block 48, it being fixed in position on said sleeve by a suitable nut a^{20} and a dowel-pin a^{21} . (See Fig. 5.)

The sleeve 48^{xx} has extended through it the hollow rod or bar 59, said rod receiving in its lower end the second or under thread, to be led into the under or second thread carrier 51, the thread being led out from said rod at the point 51^x , (see Fig. 10,) and then through a hole 60^x in the block 48. This rod 59 has fixed to it below said gear 45 a ball a^{22} , said ball being, as herein shown, embraced, as it preferably will be, between two loose cup-shaped disks a^{23} and a^{24} , said disks loosely surrounding said rod and contacting with said ball, said disks resting on forks a^{25} a^{26} of a lever a^{27} , pivoted at a^{28} between depending hangers a^{29} , connected in suitable manner, as by screws a^{29x} , with the loop-shaped depending portion a^{41} , hereinbefore referred to. This lever a^{27} is connected with the rod f^9 , common to said patent, and the movement of said rod, actuated as provided for in said patent, moves the lever a^{27} and reciprocates the rod or bar 59, also common to said patent; but herein the said rod f^9 is connected in a novel manner with the lever by especial devices of my invention, to be hereinafter described. The connection between the said rod f^9 and said lever a^{27} is herein effected by novel means—as, for instance, the end of the lever a^{27} is forked, and between said forks I place a block a^{30} , (see Fig. 1^a), said block being mounted on a stud-screw a^{31} , both the said block and said screw being provided with a hole, through which is passed loosely the end of said rod, suitable adjusting-nuts, as a^{33} and a^{34} , being applied to said rod above and below said block. This form of joint or connection between said rod and lever enables the strain on the rod and block to be in one and the same straight line, and the tendency of clamping and binding of the parts at that end of the lever is entirely done away with.

The rod 59 near its upper end has an attached roller or other stud b^{10} , which enters the cam-slot b^{12} in the cam part b^{13} of the multipart looper-carrier. This looper-carrier is shown as composed of three parts, (see Fig.

- 7.) the main or body part b^{14} , the cam part b^{13} , and the swiveling part b^{15} . The cam part has a hole, as b^{16} , to fit over one end of a tubular hub or projection b^{17} of the body part b^{14} , said cam part having a hole b^{18} to receive a stud-screw b^{19} , by which to positively connect said cam part to said body part. The body part has, as shown by dotted lines, Fig. 2, a hole, which receives in it loosely a stud-screw b^{18X} , the upper end of said screw entering a suitable threaded hole in the swiveling part b^{15} . The swiveling part has connected to it by a suitable screw b^{21} the looper 63, common to said patent. The swivel part b^{15} , supported as described, is free to be turned with said screw b^{18X} as a pivot or center on the body of the looper-carrier as the latter is turned about the stud-screw b^{22} , which forms the fulcrum for the multipart looper-carrier; said stud-screw entering a suitable threaded hole in the extended part 49, hereinbefore referred to.
- The looper has to be vibrated with its stud b^{18X} as it is being swung about the stud-screw b^{22} to enable the looper to properly enter the loop of needle-thread and to then expand it and put it in proper position to be entered by the under-thread carrier, the latter after entering the loop of needle-thread held by said looper rising for the buttonhole-slit and in turn presenting its loop of second or under thread above the material in which the buttonhole is being made, putting it into position to be entered by the needle in its next descent through said material back from the edge of the slit, the looper in the meantime being moved backwardly in order that it may come again into proper position to enter the loop of needle-thread. This operation is repeated stitch after stitch. To vibrate this looper, as described, I have provided an independent device carried by said block 48 and represented herein as a wing c^{10} , mounted (see Fig. 5) on a rock-shaft c^{12} , having its bearings in the said block 48, the lower end of said rod having attached to it a roller or other stud c^{13} , which is acted upon by the cam-shaped end of an arm c^{14} , said arm being shown as pivoted at c^{15} on a stud-screw inserted in said block 48. This cam-shaped arm presents at its acting end two inclined or cam faces, (see Fig. 5,) which act alternately upon said roller or other stud to rock said shaft in opposition to the stress of a spring c^{16} , said spring being represented as attached at one end (see Fig. 4) to an arm c^{17} , the opposite end of said spring being in turn attached to the swiveled part b^{15} of the looper-carrier. The part b^{15} also has screwed into it and extended therefrom laterally a pin or stud c^{18} , threaded to be screwed into the body part b^{15} , so as to project therefrom for the proper length, the threaded end of said stud receiving on it a nut c^{18X} , (see Fig. 6,) by which to hold the said pin or stud in its adjusted position, the wing c^{10} striking against the end of this stud, and by adjusting the stud the position of the looper may be determined to a nicety, it being necessary, as will be understood, that the looper should have its movements defined exactly to coöperate properly with the under-thread carrier 51 and the needle b^{18X} .
- The needle-carrier 50 is provided with a thread-guide 81, and said carrier has extended from it through a slot in the raceway 49 a stud-screw d^{10} , over which fits one end of a link d^{12} , (see Fig. 6,) said link being in turn connected by a stud-screw d^{13} with the upper end of a lever d^{14} . This lever has its upper end forked, as at d^{10X} , and at its opposite end it has a right-angled arm d^{15} , herein represented as made hollow and slotted through both sides, as at d^{16} , (see Fig. 8, which shows a section through said arm in the line x , Fig. 5,) said arm having at one end an eye d^{17} , which receives in it an eccentric bushing d^{18} , (shown in detail in Fig. 10,) said bushing being held in position by a suitable set-screw d^{19} , said eccentric forming the fulcrum for said lever d^{14} , and by turning said eccentric the stroke of the said segmental block and its attached thread-carrier may be adjusted to a nicety. The hollow arm d^{15} has a projecting ear d^{20} , which is shown as traveling behind a gib d^{22} , fast on the block 48, which, it will be understood, has imparted to it at proper times semicircular movements by or through a sector-lever 100, which derives its motion from a suitable cam, suitably described and illustrated in United States Patent No. 655,637, dated the 7th day of August, 1900. The hollow arm d^{15} receives within it a slide or loose connection d^{23} , (shown best in Fig. 5,) said slide having a hole through it transversely, said hole receiving a bushing d^{24} , surrounding a stud or screw d^{25} , said stud or screw beyond said bushing entering a threaded opening in the reciprocating rod or bar 59, said stud or screw also being passed through the slot d^{16} of the hollow arm and standing in an inclined position in said bar. This method of connecting the lever d^{14} and the reciprocating rod or bar 59 enables said rod to vibrate said lever in a plane parallel to the plane of inclination of the raceway and move the needle-carrier without the parts binding or straining one with relation to the other, owing to the different paths in which the said rod and lever move.
- It will be noted that the plane of movement of the needle-carrier 50 must be inclined to the path of the needle in order to allow of the proper concatenation of the threads, and since the rod 59 reciprocates in a path parallel to that of the needle adequate provision must be made in the connection between the inclined needle-carrier 50 and the reciprocating rod for the difference in the planes of movement. The lever d^{14} is placed in a plane parallel with the plane of movement of the needle-carrier, and hence the connection between the needle-carrier and the upper end of the lever is a simple one; but it is necessary that the pin d^{25} on the rod 59 be inclined

to compensate for the inclination of the plane of movement of the lever and also that provision should be made for the change in the distance between the pin d^{25} and the fulcrum 5 of the lever d^{14} .

The cam-shaped arm c^{14} has a slot in which is fitted to slide loosely a block e^{10X} , (shown in section in Fig. 11,) said block having through it a hole in which is fitted loosely the 10 eccentric e^{10} . The eccentric has a flange e^{18} , which when in position contacts with said block. The eccentric has extended through it a stud-screw e^{20} , which enters a threaded hole d^{25X} in the bar or rod 59, the 15 turning in of said screw confining the eccentric in its adjusted position in said block. By adjusting the eccentric about said screw in said block the block is made to occupy a position more or less distant from the fulcrum c^{15} of said cam c^{14} , and the extent of movement of the cam-shaped end of the bar may thereby be exactly adjusted.

The bar 59 has (see Fig. 2) a screw f^{10} standing in a threaded hole f^{40} , said screw being 20 extended therefrom between two like gibs f^{12} , said gibs being secured adjustably to ears of the circularly-moving block 48 by suitable screws f^{13} , the heads of said screws entering counterbored holes in said gibs, the screws 25 and their heads being smaller than the holes and counterbored portions, (see Fig. 12,) so that the gibs may be adjusted one toward the other when said screws are loosened to compensate for any wear between said screw f^{10} and the said gibs. The screw f^{10} in the descent of the bar 59 acts on one end f^{14} of a take-up or thread-controller, shown as a lever f^{15} , pivoted on a stud-screw f^{16} , inserted in an ear of the circularly-moving block 48, 30 one arm of said lever being acted upon by a spring f^{17} , said spring moving the said lever as the bar rises. This lever f^{15} co-operates with the under or second thread between the tension device 80 and the under-thread guide 45 81, and as the under-thread carrier rises it takes up the slack thread which would be formed by that movement, the lever f^{15} by holding the under thread preventing the looper from engaging said under thread as 50 the looper moves backwardly. The movement of the lever f^{15} by the spring ceases before the needle 51 or under-thread carrier completes its ascent, and said lever f^{15} remains substantially stationary until the under-thread carrier arrives with its eye in or 55 below the work, when said lever is moved by the screw f^{10} to thus hold the thread under a uniform strain. The extent of movement of the lever f^{15} by or through the spring f^{17} is 60 limited by an adjustable stop f^{20} .

In the machine herein described it will be understood that the revolute block containing the under-thread-carrying needle and the looper is rotated a little more than for a complete rotation during the production of each buttonhole, and this rotation of the block was provided for in United States Patent No.

498,216; but therein the lever actuated by the rod f^9 was connected by a pin-joint with one side of a sleeve fitted upon the lower end of 70 the rod 59; but such connection in practice has been found objectionable, for the reason that the movement of the end of the lever in the arc of a circle produces unequal strains upon the rod 59, causing its bearings to be 75 rapidly worn, and consequently I have aimed to provide means whereby the rod f^9 may be made more durable and whereby the wear between itself and its bearings in the rotatable block may be reduced to a minimum 80 and also in case of wear that I may compensate for the same by adjustment of parts. I effect this purpose by providing the bar 59 with the ball a^{22} and fitting upon said ball the cup-shaped washers a^{23} and a^{24} , and I 85 double-fork the lever a^{27} at its end contiguous to said rod that the vertical notch of the lever might span the rod, the horizontal notch forming seats for the larger bases of the washers a^{23} and a^{24} , and to provide for any wear 90 between the washers and the ball I provide the forked end of said lever with an adjusting-screw w^{10} . (See Fig. 1.)

Having fully described my invention, what I claim as new, and desire to secure by Letters 95 Patent, is—

1. A sewing-machine comprising a rectilinearly-reciprocating needle, a circularly-moving block having a raceway inclined with respect to the path of movement of said needle, means to rotate said block, a needle-carrier located in said raceway and provided with an under-thread-carrying needle, a lever mounted upon the circularly-moving block and vibrating in a plane parallel to the plane 100 of inclination of the raceway, means to connect said lever with said needle-carrier, a rod or bar, means to move it in a path parallel to that of the rectilinearly-reciprocating needle, and means to connect said lever and rod or 105 bar, whereby the movement of said rod or bar effects the movements of the parts referred to without binding.

2. A sewing-machine comprising in combination, a circularly-moving block having a 115 raceway, a needle-carrier movable therein and provided with an under-thread-carrying needle, a lever, means to connect it with said needle-carrier, said lever having at one end a laterally-extended hollow arm slotted at its 120 side, a slide fitted loosely in said hollow arm, a vertically-reciprocating bar, and a pin connecting said bar and slide; combined with means to move said bar to vibrate said lever and actuate said under-thread-carrying needle, substantially as described.

3. A sewing-machine comprising in combination, the following instrumentalities, viz: a circularly-moving block having a raceway, a needle-carrier guided by said raceway, an 130 under-thread-carrying needle mounted on said carrier, a lever having at one end a laterally-extended arm, a slide connected loosely with said extended arm, means to connect

said lever with said needle-carrier, a rod mounted in said circularly-moving block and provided with a ball-shaped projection, means to connect said rod with said slide, a lever 5 having ears to embrace loosely the ball of said rod, means to move said lever to reciprocate said rod in said block, and devices to insure the rotation of said rod in unison with said block.

- 10 4. A sewing-machine comprising in combination, a circularly-moving block, means to move it, a raceway carried by said block, a needle-carrier coöperating with said raceway and provided with an under-thread-carrying 15 needle, a pivoted lever having at one end an extended arm, an adjustable eccentric forming the pivot for said lever, means to connect said lever to said carrier, a vertically-reciprocating bar, and means to connect it loosely 20 and operatively with the arm of said lever, substantially as described.

5. A sewing-machine comprising in combination, a circularly-moving block, means to actuate it, a raceway in said block, a needle-carrier fitted to slide in said raceway and provided with an under-thread-carrying needle, a pivoted lever having at one end an extended arm and provided with an ear, a guide connected with said block to guide said ear in 30 the movement of said lever, means to connect said lever with said carrier, a rod, means to actuate it, a slide coöperating loosely with the extended arm of said lever, and means to connect said slide with said rod whereby the 35 reciprocations of said rod effect the movement of said lever about its pivot, substantially as described.

6. In a sewing-machine, the following instrumentalities, viz: a reciprocating eye-pointed thread-carrying needle to penetrate the material, means to operate it, a circularly-moving block, a looper coöperating with said needle, a looper-carrier composed of a body part, a cam part, and a swiveled part to which said 45 looper is attached, means to move said looper-carrier, and means comprising a wing, a rock-shaft, and a suitable cam to move said rock-shaft to turn the swiveled part of said looper-carrier on its body part.

50 7. In a sewing-machine, the following instrumentalities, viz: an eye-pointed thread-carrying needle to penetrate the material, means to actuate it, a looper, a looper-carrier composed of a body part and a swiveled part mounted thereon, means to sustain and actuate said body part, a pin or stud connecting the swiveled part with the body part loosely, a wing, and a rock-shaft to which said wing is attached; combined with means 55 to move said rock-shaft and cause said wing to turn the swiveled part of said looper-carrier on said body part, substantially as described.

8. A sewing-machine comprising in combination, the following instrumentalities, viz: a circularly-moving block, a looper-carrier composed of a body, a swiveled part, and a

detachable cam-slotted part, the said swiveled part having attached to it a looper, and a stud to support said body part, combined 70 with a vertically-reciprocating rod or bar having a stud to enter said cam-slotted part, and means to move said rod or bar vertically to turn said looper-carrier about its pivot, and means to vibrate the swiveled part of said 75 carrier on said body part, substantially as described.

9. A sewing-machine comprising in combination a looper-carrier, means to support and actuate it, said carrier being composed of a 80 body part and a swiveled part mounted thereon, a looper held by said swiveled part, and a rock-shaft having a wing and a projection; combined with a cam to act on the projection of said rock-shaft to turn it, a reciprocating bar or rod, means to actuate the same, and connections between said bar or rod and said cam to enable the latter to be moved with and by said rod or bar, substantially as 90 described.

10. A sewing-machine comprising in combination, the following instrumentalities, viz: a circularly-moving block, a looper-carrier composed of a body part, a swiveled part mounted thereon, said swiveled part having 95 a looper, a wing to move said swiveled part, means to sustain said wing, a slotted wing-actuating cam, having one of its ends pivoted to said block, a block entering the slot in said cam, an eccentric to sustain said block, a rod 100 or bar fitted loosely in said circularly-moving block, means carried by said rod or bar to sustain said eccentric to said rod, the adjustment of said eccentric regulating the throw of said wing and consequently timing the 105 movement of the looper.

11. A sewing-machine comprising in combination, a circularly-moving block, a bar mounted therein provided with a diagonally-placed stud, means to reciprocate said bar, 110 an under-thread-carrying needle, and a carrier therefor, combined with a lever provided with a movable slide engaged by said stud, and connections between said lever and the carrier for said under-thread-carrying needle, 115 substantially as described.

12. In a machine for stitching buttonholes, an eye-pointed needle, means to move it to penetrate the material, a circularly-movable block located below the material and provided 120 with a raceway and a stud, a needle-carrier in said raceway, an attached under-thread-carrying needle, a lever mounted on said block, and connected operatively with said needle-carrier, means to move said lever, a 125 looper, a looper-carrier composed of a body part mounted on the stud of said block, a swiveled part mounted on the body part, and a cam part attached to said body part; means to actuate said cam part to move said looper 130 in the direction of its length, an independent device carried by said block, and means to move said device in a plane transverse to that in which moves the lever for actuating the

- needle-carrier, said device acting against the swiveled part and turning it on the said body part, and means to move said swiveled part in opposition to said device.
- 5 13. In a machine for stitching buttonholes, an eye-pointed needle to penetrate the material, means to actuate the same, a coöperating under-thread carrier, means to sustain the said thread-carrier and to actuate the same, a looper, a looper-carrier composed of a body part pivotally mounted on the means sustaining the under-thread carrier, a swiveled part movable on the body part, a cam part connected with said body part; a rod 10 having two pins one entering the cam of the cam part, means to move said rod longitudinally, and a device deriving its movement from the second pin on said rod to meet and turn the swiveled part on the body part.
- 15 14. A buttonhole-sewing machine comprising a rotatable block sustaining a needle-carrier having an attached under-thread-carrying needle, a looper-carrier having an attached looper, a rod located in the axis of rotation of said block, two slotted levers sustained by said block and connected respectively operatively with said needle-carrier and said looper-carrier, means to reciprocate said rod, and studs carried thereby entering 20 slots in said levers to move them and actuate said needle-carrier and looper-carrier.
- 25 15. A buttonhole-sewing machine comprising a rotatable block sustaining a needle-carrier having an attached under-thread-carrying needle, a looper-carrier having an attached looper, a rod located in the axis of rotation of said block, two slotted levers sustained by 30 said block and connected respectively operatively with said needle-carrier and said looper-carrier, means to reciprocate said rod, studs carried thereby entering slots in said levers to move them and actuate said needle-carrier and looper-carrier, and means also carried by said block to move a part of the looper-carrier laterally as described when making a 35 stitch.
- 40 16. A buttonhole-sewing machine comprising in combination, a rotatable block provided with an under-thread-carrying needle, a rod located in the axis of rotation of said block, said rod being provided near its lower end with a ball, and a pivoted lever cross-forked at its end to embrace said rod and reciprocate it in said block.
- 45 55 17. A buttonhole-sewing machine comprising in combination, a rotatable block provided with an under-thread-carrying needle, a rod located in the axis of rotation of said block, said rod being provided near its lower end with a ball, suitable cup-shaped washers embracing said ball, a pivoted lever cross-forked at its end to embrace said rod and act upon said washers, and means to reciprocate said lever to reciprocate said rod in said block.
- 50 18. A buttonhole-sewing machine comprising in combination, a rotatable block provided with an under-thread-carrying needle, a rod located in the axis of rotation of said block, said rod being provided near its lower end with a ball, suitable cup-shaped washers embracing said ball, a pivoted lever cross-forked at its end to embrace said rod and act upon said washers, means to reciprocate said lever to reciprocate said rod in said block, and adjusting means to adjust the lever to compensate for any wear between the disks and the ball of the said rod.
- 55 19. A buttonhole-sewing machine comprising in combination a rotatable block and means for rotating the same, lower complementary stitch-forming mechanism located on said block, a rod located in line with the axis of rotation of said block, connections between said rod and said lower complementary stitch-forming mechanism for operating the same, a ball connected with said rod, washers co-operating with said ball, and means acting upon said washers to reciprocate said rod during the period of rotation of the block and while the stitching of the buttonhole is being carried on and completed.
- 60 20. In a buttonhole-sewing machine comprising in combination, a rotatable block containing a looper-carrier composed of a body, and a block swiveled on said body and provided with a looper, a stud projecting from one end of said swiveled block, a wing, a rock-shaft carrying said wing, and means to move said rock-shaft to cause the wing carried thereby to periodically contact with the said stud and thus turn the swiveled part of the looper-carrier on the body part thereof.
- 65 In testimony whereof I have signed my name to this specification in the presence of two subscribing witnesses.
- 70 WILLIAM W. DIXON.
- 75 Witnesses:
EDWARD F. ALLEN,
GEO. W. GREGORY.
